[57] **CLAIM**

The ornamental design for a depilatory dispenser, as shown.

DESCRIPTION

FIG. 1 is a top plan view of a depilatory dispenser showing my new design;

FIG. 2 is a front elevational view thereof, the rear elevational view being identical to the front elevational view;

FIG. 3 is a right side elevational view thereof, the left side elevational view being the same as the right side elevational view; and

FIG. 4 is a bottom plan view thereof.

FIG. 1

FIG. 2

FIG. 3

FIG. 4
